CLAIM

Mar. 20, 2002 (JP) 2002-007441

The ornamental design for a pressure contact terminal for power supply jack, as shown.

(51) **LOC (7) Cl. 13-03**

DESCRIPTION

(52) **U.S. Cl. D13/133**

FIG. 1 is a front left top perspective view of a pressure contact terminal for power supply jack showing our new design;

(58) **Field of Search** D13/133; 439/746, 439/749, 834, 862

FIG. 2 is a rear right top perspective view thereof;

(56) **References Cited**

FIG. 3 is a front elevational view thereof;
